**EQUIPMENT DESIGNED TO REGULATE THE FLOW OF,
PREFERABLY, A STERILE LIQUID AND A
DISHWASHING LIQUID OR A STERILIZING AGENT**

This invention relates to a piece of equipment for the regulation of the flow, preferably, a sterile liquid and dishwashing liquid or a sterilizing agent, comprising a valve having valve units, each of which valve units comprises a valve disc and a valve spindle, the units being designed to be capable of movement between different positions in order that the equipment should be capable of assuming both a filling position, in which position the valve discs are situated at the positions in which the valve allows flow of the sterile liquid while at the same time entry of the dishwashing liquid and the sterilizing agent is prevented, and also a dishwashing and/or sterilizing position, in which position the valve discs are situated at positions in which the valve allows flow of the dishwashing liquid and/or sterilizing agent while at the same time entry of the sterile liquid is prevented.

In, for instance, sterile packaging technology, arrangements of valves often separate different substances that cannot be permitted to come into contact and to contaminate one another. In aseptic packaging lines, the equipment for sterilization of the goods to be packaged is generally designed in such a way that a number of packaging machines can be served simultaneously, there being used at least one main pipe line for transmission of the sterile goods, and the construction is often such that the packaging machines extract their share of the goods to be packaged into the containers directly from the main pipeline. When, for various reasons, a packaging machine must discontinue production for a short or long period, it is necessary to wash and sterilize the machine in question. It has been found however that when one or more machines, which form part of a packaging line consisting of several packaging machines, are being washed and/or sterilized, washing and sterilization of these machines, if the rest of the process is not to be affected from the bacteriological and hygienic points of view, is only possible if complicated equipment is installed and an unjustifiable number of valves used. For reasons of bacteriological and hygienic considerations, a valve that is to separate different substances from one another or, as in the case being described, separate the goods to be packaged from e.g., dishwashing liquid in an adjacent space, must be capable of assuming a position where a double seal is attained. The space between the seals should furthermore be flushed by a suitable flushing agent. In the case being described, the flushing agent should be a substance neutral to the sterile goods to be packaged, e.g., superheated steam.

The aim of this invention is thus to satisfy, inter alia, the requirements specified on the basis of bacteriological and hygienic considerations, and the invention is therefore principally characterized by the valve of the equipment being such that when the valve discs have assumed their positions in the dishwashing and/or sterilizing position of the equipment, there will be situated a distinct space principally between the valve discs, which space will communicate with the inlet and outlet pipes for the flushing agent.

Since the equipment in accordance with the invention has been exemplified for the flow of a sterile substance, it is important that the passage of the valve units through the valve should always be germ free, and for this reason the invention is further characterized at least during the operational period of the equipment, by the fact that the valve units, in the vicinity of their entry through the walls of the valve housing, are always surrounded by flushing agent. The flushing agent in this case is superheated steam which is neutral from the hygienic point of view.

It is also essential that one of the seals of the said double seal should be guaranteed by at least two forces that are independent of one another.

Further characteristics as well as advantages and aims of the invention will be evident from the constructional form of the invention which will be described below by reference to the attached schematic drawings, of which

FIG. 1 shows the equipment with the valve units in the present exemplification in the dishwashing and/or sterilization position, and

FIG. 2 shows the equipment according to FIG. 1 with the valve units in the filling position of the equipment.

The equipment shown in FIG. 1 forms part of an aseptic packaging line for liquid goods and exhibits a valve housing 1, a main pipeline 2 for transmission of the sterile liquid to the flow system shown in the figure, a filling pipe 3 through which the liquid is drawn off when the equipment has assumed the position shown in FIG. 2, and a washing and/or sterilizing pipe 4 through which dishwashing liquid or a sterilizing agent is admitted to the system. FIG. 1 also shows a first valve unit 5 and a second valve unit 6. The valve units 5, 6 have valve discs 7 and 8 and valve spindles 9 and 10 respectively. In the positions the valve units occupy in FIG. 1, the valve disc 7 is in contact with a valve seat 11 and the valve disc 8 with a valve seat 12. The valve discs 7 and 8 also have facings 37 and 38 respectively, made from material suited for the operation at hand, in this case rubber bonded to the valve discs. In the valve spindle 9 of the first valve unit 5—the inner spindle—there is a duct 15 which through orifices 16 discharges into a space 13 situated mainly between the valve discs 7, 8. The said space 13 is formed when the valve units have assumed the positions shown in FIG. 1. The space 13 is in communication with flushing agent inlet and outlet pipes 21 and 22 respectively, fitted into the wall of the valve housing 1. Supply of the flushing agent to the space 13 takes place through a passage 17 situated between the second valve unit 6 and the wall of the valve housing 1, a duct 18 situated in the valve spindle 10 of the valve unit 6, the inlet 14 to the duct 15 inside the inner valve spindle 9 and through the duct 15 and its orifices 16 into the space 13. Removal of the flushing agent from the space 13 takes place through a passage 19 situated between the inner valve spindle 9 and the valve unit 6, a duct 20 situated in the valve spindle 10 of the valve unit 6 and through the passage 40 into the outlet pipe 22. Seals 23, 24, 25 and 26, one of the duties of which is to alter the communication routes of the flushing liquid in the different positions of the valve units—see FIGS. 1 and 2—and to limit the spread of the flushing liquid in the passages, are fitted on the valve spindles. The valve housing 1 also has seals 27 and 28, one of the duties of which is to limit the spread of the flushing liquid in the passages 17 and 40. The seals may have any shape and be made from any material whatever that is suitable for the purpose at hand. In the present constructional form of the invention, however, sealing rings of rubber have been found suitable.

The power source for the operation or changes in position of the valve units 5 and 6 may be in the first place a piston motor not shown in the Figures, the transmission unit of which has been denoted 31 in FIG. 1. The transmission unit 31 actuates the valve units 5 and 6 through a circlip 33. A spring 29, which also actuates the shifting of the valve units to the positions shown in the Figures and conditions their seating onto the valve seats 11 and 35, is also situated inside the valve unit 6. The spring 29 is fixed between the valve unit 6 and a fixture 30 fitted on the inner valve spindle 9.

The operation of the equipment and the method of working of the valve are as follows: In FIG. 2, the equipment is shown in the position assumed when a packaging machine is in operation, i.e., when appropriate amounts of the sterile goods to be packaged are being delivered, during which operation the valve and valve units have assumed a filling or open position relative to the main pipe 2. The sterile goods to be packaged, carried along the main pipe, thus flow through the valve, entering it through the inlet 32 and being discharged through the fill pipe 3.

If the machine in question, which is usually connected to a circuit of several machines, is stopped, entry from the main pipe 2 of the goods to be packaged is shut off by the valve—see FIG. 1.

This is accomplished by the power source, e.g., a piston motor which is not shown in the Figures, receiving an impulse

whereupon the transmission unit 31 of the piston motor, which in the filling position of the equipment has actuated the valve spindle 9 of the first valve unit 5 by means of a pull transmitted through the circlip 33 fitted on the unit 31—see FIG. 2—begins to move in a direction towards the valve spindle 9. As a result, the valve disc 7 fitted on the valve spindle 9 will be forced away from the second valve unit 6, owing to the fact that the spring 29, which in the filling position of the equipment is compressed, has a chance to expand, since it is affixed between the valve unit 6 and the fixture 30 fitted on the inner valve spindle 9. Further expansion of the spring 29 is prevented when the circlip makes contact with the valve spindle 10 of the valve unit 6, after which the valve units 5,6 are displaced simultaneously—the valve unit 6 by the circlip 33 and the valve unit 5 by the spring 29—with their valve discs 7 and 8 seating on valve seats 11 and 12 respectively. During this process, the valve disc 7 of the first valve unit 5 will reach its valve seat 11 a little before the valve disc 8 of the second valve unit 6 reaches its valve seat 12, which means that the spring 29 will be compressed somewhat. When the valve discs 7 and 8 are in contact with their seats 11 and 12 respectively, the equipment has assumed its dishwashing and/or sterilizing position, which means that inflow of the sterile goods to be packaged is shut off and also that the washing and/or sterilizing agent is at the same time admitted into the valve from the pipe 4 through the opening 34, and also that there is formed a sealed and distinct space 13 mainly between the valve discs 7 and 8. At the same time that the valve discs 7 and 8 assumed their positions in the washing and/or sterilizing position of the equipment, the sealing rings 23, 24, 25 and 26, fitted on the valve spindles 9 and 10, also assumed positions such that the passages 17, 41, 19 and 40 as well as the ducts 18, 15 and 20 have become separated in such a way that passages to and from the space 13 have been created for the flushing agent.

The flushing agent, which in the present case is superheated steam, is admitted to the system through the supply pipe 21. The steam is thereafter transported to the space 13 through the passage 17 which is delimited by the sealing ring 26 and a sealing ring 28 fitted in the valve housing 1, and then to the duct 15 in the inner valve spindle 9 through the duct 18 and the passage 41 which is delimited by the sealing rings 24 and 25. The exit route of the steam from the space 13 consists of the passage 19, one end of which is connected to the space 13 and the other end is delimited by the sealing rings 24, the duct 20 and the passage 40 which is delimited by the sealing ring 26 and a sealing ring 27 fitted in the valve housing 1.

During the time that the equipment is in the washing and/or sterilizing position, the piston motor unit 31 presses onto the valve spindle 10 through the circlip 33, so that seal between the valve disc 8 and the valve seat 12 is ensured. The seal between the valve disc 7 and the valve seat 11 is guaranteed by two independent forces, namely the spring force and the steam pressure in the space 13. The steam, however, has another duty in the space 13, namely to flush and sterilize this space.

The passages 17, 40 and 19 and the sealing rings delimiting these passages, apart from their duties as communication routes, also serve as a steam seal. Since the said passages are always flushed through by the steam, which is neutral from the point of view of hygiene, in the positions of the valve shown, the passage of the valve units through the valve housing 1 will always be germfree in the washing and/or sterilizing position of the equipment.

The valve in the equipment, in the washing and/or sterilizing position shown, satisfies the minimum requirement that can be specified, namely that there should always be at least two seals between the goods to be packaged and e.g., a dishwashing agent, and that the space between the seals should be flushed by a cleansing agent, which agent in the present case consists of superheated steam which is capable of cleansing and sterilizing the said space.

When the packaging or filling machine has been cleansed and sterilized and is to start production again, the piston

motor exerts a pull in the other direction, whereupon the circlip 33 moves away from the valve spindle 10, as a result of which the pressure of the valve disc 8 on the seat 12 eases and at the same time the spring pressure on the valve disc 7 decreases. Since the circlip 33 is in engagement with the inner valve spindle 9, the valve disc 7 and, via the spring, the valve disc 8 as well, is drawn down towards the valve seat 35—see FIG. 2—in order to seal off the passage 34 and at the same time open the valve to admit and allow flow of the sterile goods through the valve. During this change in position of the valve units 5 and 6, the piston motor will continue to pull downwards the inner valve spindle 9 even after the valve disc 8 has come in contact with the valve seat 35, until such time as the valve disc 7 forms a seal around the top 36 of the valve disc 8. The result of this is that the spring 29 will be compressed and that the seal of the valve disc 8 with the valve seat 35 is guaranteed during this so-called filling position, both as a result of the fact that, all the time that the equipment is in this position, the piston motor maintains its pressure on the inner valve spindle 9 which forces the valve disc 8 down onto the valve seat 35 via the valve disc 7, and also as a result of the compressed spring 29 exerting pressure.

At the same time that the valve units 5 and 6 have changed their positions, the sealing rings 23–26 fitted on the valve units have also assumed new positions—see FIG. 2. The communication routes of the steam to the passages 17 and 14 and to the ducts 18 and 15 have therefore been closed. In this filling position of the equipment, the duty of the steam, together with its new communication routes, is principally to act as a steam seal, in order that the passage of the valve units through the wall of the valve housing 1 should be kept germfree all the time in this position also. Steam is admitted to the system as before through the inlet pipe 21, but its circulation is different. Steam will thus circulate in the passage 40 and, through the duct 20, also inside the passage 19. Spread of the steam in the passage 19 is now limited by virtue of the fact that sealing ring 23 shuts off communication with the previous space 13 in the washing and/or sterilizing position of the equipment.

One of the reasons why spread of the steam in the passage 19 is limited by the sealing ring 23 is to prevent the steam from having an opportunity of actuating the inner piston, and at the same time, together with the seal 39 between the valve disc 7 and the top 36 of the valve disc 8, to prevent leakage of the flushing agent into the product.

The equipment described and illustrated is capable of utilization in fields other than the sterile packaging industry, for instance in chemical engineering. It will be evident that this equipment is especially useful in all piping systems where different substances are to be transmitted through the system at different times, i.e., where the various substances are to be separated. This is particularly the case where the substances are kept in adjacent spaces. It must be pointed out once again that, despite its simple construction and operation, the valve has the particularly advantageous property of being capable of separating different substances by means of a double seal, and of offering the possibility at the same time of the space between the seals being flushed with a cleansing, dishwashing or sterilizing agent. These agents may naturally be substances other than steam. The agent to be used is dependent on the purpose for which the equipment is to be used, but a chemical catalyst or reagent may be quoted as examples.

The material of the valve housing and valve units is also dependent on the purpose for which the equipment is to be used, but in the preferred constructional version, the valve housing should preferably be made of acid- and corrosion-resistant material, but such material that will not contaminate the food-stuff in question.

The construction and design of the equipment may naturally differ in a number of ways from that shown, without the idea underlying the invention being deviated from. The shape and extent of the passages may thus be different and also the design of the valve spindles and valve discs. The invention is therefore not limited to the case exemplified and by the variations mentioned, but only by the following claims.

I claim:

1. A valve structure for controlling the flow of a first liquid through a pipe and for controlling the flow of a cleaning fluid through the pipe when the first liquid is stopped, comprising, a pipe, a first valve for controlling the flow of the first liquid into said pipe, a second double-acting valve for controlling the flow of the cleaning fluid into said pipe, said second valve when open to the cleaning liquid being closed to the first liquid to supplement the closure of said first valve in serial disposition therewith, means for actuating said first and second valves whereby when said first valve is open said second valve is open to the first liquid and is closed to the cleaning liquid and when said first valve is closed to the first liquid said second valve is open to the cleaning liquid, said first valve and said second valve forming a space therebetween in the latter valving position which is sealed from said pipe and the cleaning fluid and means for flushing said space with a flushing agent.

2. A valve structure as claimed in claim 1 wherein said valve actuating means comprises concentric valve spindles, the inner spindle actuating said first valve and the outer spindle actuating said second valve.

3. A valve structure as claimed in claim 2 wherein said valve actuating means further comprises means for relatively displacing said concentric valve spindles.

4. A valve structure as claimed in claim 2 wherein said inner spindle is provided with an axial duct for supplying flushing agent to said space.

5. A valve structure as claimed in claim 4 and further comprising a housing, and wherein said concentric valve spindles pass through the wall of said housing and said concentric valve spindles are spaced from each other and the outer spindle is spaced from the wall of said housing.

6. A valve structure as claimed in claim 5 wherein said concentric spindles and the wall of the housing are provided with seals spaced longitudinally along the axes thereof.

7. A valve structure as claimed in claim 6 wherein the said spindles are provided with ducts providing communication through the wall of the inner spindle and through the wall of the outer spindle.

8. A valve structure as claimed in claim 7 wherein the ducts and said seals provide passages for the flushing agent.

9. A valve structure as claimed in claim 8 and further comprising means for relatively displacing said concentric valve spindles whereby different passageways are established by said seals and ducts provided therein.

10. A valve structure as claimed in claim 9 wherein passageways are provided for passage of the flushing agent to the space between said first valve and said second valve when said first valve is closed to the first liquid and the second valve is open to the cleaning liquid.

11. A valve structure as claimed in claim 10 and further comprising means for limiting the passage of the flushing agent to the space between the inner and outer valve spindles when said first valve is open to the first liquid and the second valve is closed to the cleaning liquid.

12. A valve structure as claimed in claim 1 and further comprising a housing, said valve actuating means passing through the wall of said housing and means for surrounding said valve actuating means where it passes through said housing with the flushing agent.

13. A valve structure as claimed in claim 1 and further comprising valve seats in said pipe for said first valve and for both positions of said second double-acting valve.

14. A valve structure as claimed in claim 1 and further comprising means for applying an additional independent force to close said first valve to stop the flow of the first liquid into said pipe.

15. A valve structure as claimed in claim 1 and further comprising spring means for urging the second valve to close off the cleaning liquid when the first valve is open to the first liquid.

16. A valve structure as claimed in claim 1 and further comprising spring means for urging the first valve to close off the first liquid when the second valve is open to the cleaning liquid.

17. A valve structure as claimed in claim 1 wherein said first valve when open to the first liquid is in sealed engagement with the second valve when it is seated to close off the cleaning liquid.
